UNITED STATES PATENT OFFICE.

JOSHUA KING NORTHRUP, OF ELLICOTTVILLE, NEW YORK.

PAINTBRUSH.

Application filed July 18, 1922. Serial No. 575,845.

To all whom it may concern:

Be it known that I, JOSHUA KING NORTHRUP, a citizen of the United States, residing at Ellicottville, in the county of Cattaraugus and State of New York, have invented new and useful Improvements in Paint-brushes, of which the following is a specification.

This invention relates to an improvement in brushes having adjustable bristles and designed more particularly for paint brushes, although it is also applicable to brushes for other purposes.

The object of the invention is the construction of a brush of this type which does away with the bridle commonly employed for stiffening the bristles of new brushes, which permits the same result to be attained by longitudinal adjustment of the bristles in the brush-stock and which at the same time furnishes a firm backing for the butt-ends of the bristles or bristle-unit in all adjustments thereof.

In the accompanying drawings: Figures 1 and 2 are longitudinal sections of the improved brush, at right angles to each other, showing the bristles drawn into the socket of the stock to their full limit. Figures 3 and 4 are similar sections, showing the bristle-head adjusted forwardly to project the bristles to a greater extent after having become partly worn off.

Similar characters of reference indicate corresponding parts throughout the several views.

10 indicates the head or stock of the brush which has a suitable handle 11 on its rear side and a comparatively deep laterally elongated socket or chamber 12 in its front side which receives the bristles 13. These are longitudinally adjustable in said socket as a unit, so that when the bristles are new and of full length, they may be drawn fully into the socket to render them sufficiently stiff, while as they become worn they may be extended more or less to give them the necessary flexibility.

For this purpose the butt-ends of the bristles are preferably bound with a band 14 and vulcanized or otherwise secured thereto and to a substantially flat transverse tongue or head 15. These parts are snugly fitted in the socket, but their depth is preferably less than that of the socket, as shown.

55 Extending rearwardly from the central

portion of the tongue 15 is a screw bolt or rod 16 which passes through a smooth longitudinal bore 17 of the handle 11 and engages a clamping nut 18 abutting against the rear end of the handle. This nut is 60 preferably provided with a reduced forward extension or sleeve 19 seated in a recess 20 in the adjacent portion of the handle. The nut may also be provided with lateral openings 21 to receive a rod or other implement 65 for tightening it.

When the bristles are new or uneven, they and their carrying head 15 occupy the position shown in Figs. 1 and 2, said head and the butt ends of the bristles bearing 70 against the inner or rear end of the socket where they are tightly held by the screw bolt 16 and the nut 18. The socket is of such dimensions as to surround the bristles to a sufficient depth to give them the desired 75 stiffness.

When the bristles become shorter by wear, the nut is removed and the bristles together with the screw bolt are removed from the socket and handle as a unit. One or more 80 shims or washers 22 of a suitable thickness are then placed in the bottom of the socket and the bristle-unit is replaced therein against the shims and again secured in place by means of the clamping nut. As the 85 bristles continue to wear, they can by this means be advanced or adjusted forwardly in the socket from time to time by inserting additional shims, thus greatly lengthening the life of the brush and at the same 90 time obtaining the desired degree of flexibility or stiffness of the bristles in all adjustments. The shims 22 which may be made of cork, rubber or like material, not only form a firm and solid backing for the 95 bristle-unit when the same is advanced or adjusted forwardly in its socket and relieve the screw-bolt and clamping nut from longitudinal strain, but they also form a seat to keep the paint from working back 100 through the handle-bore and reaching the painter's hands.

When the bristles become unserviceable, they can be readily replaced by a new unit, thus permitting the brush stock to be used 105 over and over again and effecting an important saving.

The shims 22 may be of cork or any other appropriate material and are perforated for the passage of the screw bolt 16. They 110

form a firm backing for the bristle unit in all its adjustments after wear has taken place, thus holding the unit as securely after as before the insertion of one or more shims.

The brush stock and its handle are preferably constructed of aluminum, but they may be made of any other suitable material.

I claim as my invention:

- 10 1. A paint brush of the character described comprising a stock provided with a laterally elongated socket at one side and an integral handle extending from its opposite side, said handle having a longitudinal bore 15 opening into said socket, a bristle-unit adjustable lengthwise in said socket to increase or diminish the effective length of the bristles, said unit including a substantially flat transverse bristle-attaching head having a screw bolt extending through said handle bore, backing means interposed between the butt end of the bristle-unit and the bottom of the socket and forming a seal for preventing the paint from working 20 through the handle bore, said backing means being compressible and detachable from said handle-socket, and means applied

to the end of said screw bolt for clamping the bristle-unit in place.

2. A paint brush of the character described, comprising a stock provided in its front side with a socket and an integral handle extending from its rear side, said handle having a longitudinal bore extending therethrough and opening at its front end into said socket, the opposite end of the handle being provided with a recess in axial alignment with its bore, a bristle-unit adjustable lengthwise in said socket to increase or diminish the effective length of the bristles, said unit including a transverse supporting head and an encircling band between which the butt-ends of the bristles are secured, said head having an integral screw-bolt extending rearwardly therefrom through said handle-bore into its recess, one or more shims interposed between the butt end of the bristle-unit and the bottom of the socket and constituting a solid backing for said unit, and a clamping nut applied to the rear end of said screw bolt and having a reduced forward extension engaging the recess in the adjacent end of the handle.

JOSHUA KING NORTHRUP
